UNITED STATES PATENT OFFICE

2,523,111

ELECTRIC PREHEAT UNIT FOR TUBING

Rea I. Hahn and Benjamin N. Snyder, Rochester,
N. Y., assignors to General Motors Corporation,
Detroit, Mich., a corporation of Delaware

Application May 15, 1948, Serial No. 27,275

6 Claims. (Cl. 219—11)

1

This invention relates to the manufacture of brazed steel tubing which, for example is formed from a single strip of steel into a two-ply tubing by apparatus shown in Nichols et al. Patent No. 2,195,751. The formed tubing passes through a copper tube brazing bath in a furnace containing a non-oxidizing atmosphere.

The object of the invention is to provide a simple and efficient unit for preheating the tubing before it passes into the furnace to a temperature below the temperature of the brazing bath thereby reducing the cost of construction and operation of the furnace by substantially reducing the amount of heat the furnace is required to supply.

Further objects and advantages of the present invention will be apparent from the following description reference being had to the accompanying drawings wherein a preferred embodiment of the present invention is clearly shown.

In the drawings:

Fig. 1 is a view showing the side of the preheating unit and the brazing furnace in longitudinal section.

Fig. 2 is a view in the direction of arrow 2 of Fig. 1.

Fig. 3 is a plan view of the preheating unit with an inspection window shown in section.

Fig. 4 is a sectional view on the line 4—4 of Fig. 3.

Fig. 5 is a side view partly in section of the preheating unit and drawn to a larger scale, the part in section being on line 5—5 of Fig. 3;

Fig. 6 is a sectional view on line 6—6 of Fig. 3;

Fig. 7 is an end view in the direction of arrow 7 of Fig. 3;

Fig. 8 is a sectional view on the line 8—8 of Fig. 5.

Referring to Figs. 1 and 2, the brazing furnace comprises a metal jacket 20, supported by vertical angles 21 resting on the floor indicated by line 22 (Fig. 2) and enclosing thick walls made of layers 23, 24, 25 and 26 of refractory material. The bottom wall layer supports metal I blocks 30 embedded in a layer 31 of refractory cement which support a metal base 32 which supports a brazing tray 33 of the type shown in Nichols et al. Patent 2,197,191. The tubing to be brazed passes toward the right (Fig. 1) through a tube 34, a flared collar 35, a compressed gas wiper 36, a brazing bath chamber 37, a second compressed gas wiper 38 and an outlet tube 39. This gas is non-oxidizing. The furnace is heated by electrical elements 40. Copper for the brazing bath is supplied by copper wires which pass down

2

through a tube 41, and are melted by the heat of the furnace. Non-oxidizing gas is introduced into the furnace through a pipe 42. The temperature of the furnace is automatically regulated through the use of a pyrometer 43. The right end wall of the furnace includes a refractory block 45 having an opening 46 which can be closed by a door 47 having a long notch 48 therein for clearing the tube 39. The door is raised and lowered by the use of the crank 50 connected with a drum 51 around which passes several turns of cable 52 connected at the lower end with weight 53 and passing around guide pulleys 54 and 55 and connected with the door.

The preheat unit is mounted on a table 60 located adjacent the left end wall of the furnace. As viewed in Fig. 6, the table 60 has parallel angle bars 61 supporting rails comprising plates 62, 63 and 64 connected with angles 61 by screws 65 and nuts 66. The rails guide a horizontally movable base 70 to which a rack 71 is attached. Rack 71 meshes with a pinion 72 integral with a shaft 73 journaled in a bearing 74 attached to an angle 61 and operated by handle rods 75 attached to a hub 76 which is connected with a shaft. By turning the shaft 73, the location of plate 70 and the preheating unit supported thereon can be adjusted horizontally. The tubing to be preheated passes first between two copper rollers 80 and 81 (Fig. 8) attached respectively to a steel shaft 82 and to a copper shaft 83 journaled respectively in bearing bushings 84 and 85 of carbon or other bearing material having good electrical conductivity. Washers 82a and 83a secured to shafts 82 and 83 respectively by screws 82b and 83b respectively retain these shafts within their bearings. Bearings 84 and 85 are supported respectively by a steel bracket 86 and by a copper bracket 87. Bearing 84 is retained by a ring 84a attached to bracket 86 by screws 84b. Bearings 85 are retained by a ring 85a attached to bracket 87 and by a ring 191 attached by screws 190 to bracket 87. Screws 88 attach the bracket 87 to plates 89 which support a pin 90 which supports plate 91 attached by screws 92 to bracket 86. Thus bracket 86 can be moved into position 86' (Fig. 8) to facilitate threading the tube. Screws 94 (Fig. 5) attach the bracket 87 to a nonconducting plate 95 which screws 96 attach to the base 70.

Base 70 (Figs. 3 and 6) has integral brackets 100 supporting bearing sleeves 101 on which a tubular shaft 102 is journaled. The shaft 102 pivotally supports arms 103 which are welded to a metal plate 104 which together with plates

103 and 106 form side and top walls of a case section J whose left end wall (Fig. 3) is provided by a plate 107 attached by welding to plates 104, 105, 106 and whose right end wall is provided by movable plate 108 secured by screws 110 to plate 105. Screws 111 and 112 respectively secure blocks 113 and 114 of refractory, non-conducting material which supports a block 115 of similar material. Between the left ends (Fig. 3) of blocks 113 and 114 and plate 107 there is a refractory block 107a which is notched to provide an opening for the tubing and a bar 125 (also Fig. 5). Between the right ends of blocks 113 and 114 and plate 108 there is a refractory block 108a attached by screws 109 to plate 108. Block 108a is notched to provide an opening for the tubing and to receive a refractory block 108b secured by screws 108c to a plate 131.

A screw 129 secures to the shaft 102 a bracket 121 to which screws 122 attach a bus bar 125, said screws and bus bar being insulated by bushings 124 through which the screws pass and by an insulating plate 123. The bar 125 extends over into the chamber in case section J and there it supports a carbon block 126 located between a copper block 127 and a stainless steel block 128 adjacent to a stainless steel plate 128a which, by turning a screw 129 is caused to press against the block 126 to hold it against block 127. Block 126 has a groove 126a for receiving the tubing T. The parts 127 and 128 are secured to the bus bar 125 by screws 130 which also retain a plate 131 insulated from the bus bar 125 by a non-conducting plate 132 and insulated from the screws by non-conducting bushings 133. The case section J rests upon the plate 132 and is free to be moved clockwise about the rod 102 when it is desired to uncover the block 126 when threading the tubing through the heating unit.

To plate 131 (Fig. 4) two metal plates 135 are welded and between these plates is located a non-conducting refractory plate 136 which supports a metal case section K comprising a top plate 137 side plates 138 and strips 138a united by welding. These plates enclose side blocks 139 and a top block 140 of non-conducting refractory material. The blocks 139 are secured to the walls 138 by screws 138b (Fig. 3). Clips 141 retained by screws 142 secure the block 140 and the plate 136 to parts 137 and 131 respectively. Plate 136 has an opening 146 aligned with a pipe tapped opening 147 in plate 131 for making connection with a pipe through which non-oxidizing gas is introduced.

The tubing can be readily threaded through the heating unit since the roller 80 can be elevated above the roller 81, and the case section K can be removed from its supporting plate 136 and the case section J can be moved upwardly from its supporting plate 132 by swinging it about the shaft 102.

Good electrical contact between the tubing and carbon block is obtained by weighted carbon blocks 150 (Fig. 5) which are guided for vertical movement by the block 115. The blocks 150 are attached to rods 151 which support weights 151a and pass through holes in bar 152 which screws 153 attach to a block 154 attached to the upper plate 105. As the blocks 126 and 150 wear due to abrasion by the tubing, the blocks 150 descend to maintain engagement of the tubing with block 126 under constant pressure. As the case section J is moved clockwise (Fig. 6) about the shaft 102 to expose the block 126, for threading

the tubing, the weights 151a can descend upon the bar 152 which limits downward movement of the blocks 150 relative to the block 115 so that portions of the blocks 150 remain in the notches in block 115. If the case section J is moved about the shaft 102 far enough to cause the weights 151a to gravitate away from the bar 152, such movement of the weights is limited by engagement of the weights with the bar 152.

After threading the tubing through the groove in the block 126 the case section J is returned to normal position; and, during this return movement, the blocks 150 move downward until they engage the tubing and, thereafter, the plate 152 moves downward relative to the rods 151.

The structure supported by shaft 102 can be rotated about the axis of shaft 102 in order to locate the tubing at the desired horizontal level as the groove 126a in block 126 deepens due to wear. This is accomplished by an adjustable strut including a nut 160 (Fig. 7) which is threaded on a rod 165 attached to a block 166 which a pin 167 pivotally connects to a block 168 attached to the plate 70 by screws 169. The nut 160 has a shank 161 received by notch 162 in a plate 163 welded to plate 131. The flange 164 of the nut 160 carries part of the weight of the parts pivotally supported by the shaft 102. When it is desired to move these parts clockwise and upwardly the rod 165 is moved counterclockwise about its pivot pin 167 so that the nut 160 is clear of the plate 163.

The side wall 106 (Fig. 3) is provided with an opening therethrough and in alignment with the opening there is a collar 180 welded to the plate 106 which supports a sight glass 181 retained by ring 182.

The tubing is heated by the passage of electric current from a direct or alternating current source one terminal of which is connected with bus bar 125 by a flexible conductor not shown and whose other terminal is connected with bus bar 194 (Fig. 8) attached by screw 192 and nut 193 to a bar 191a integral with ring 191 which screws 190 attach to bracket 87. The area of contact between the tubing and the block 126 is substantial and consequently the voltage drop between the block and tubing is relatively low. Most of the voltage drop is due to heating the tubing between the block 126 and roller 81. Since the voltage of the tubing where it contacts the rollers 80 and 81 is relatively low there is substantially no arcing between tubing and the rollers. Some of the current can pass from the tubing to the bus bar 194 through roller 80 and its bearing 84 and bearing bracket 86, plate 91, pin 90 and plates 89.

The tubing is moved through the heating unit and the furnace toward the right in Fig. 1 by the apparatus which forms the tubing from a steel strip, and also by a tubing wind-up reel (not shown) located adjacent the right end of tube 39 which provides a chamber enclosing a non-oxidizing atmosphere in which the tubing cools between the furnace and the reel.

By turning the shaft 73 counterclockwise by handles 75, the preheating unit can be moved away from the brazing furnace when greater access to the left end of the furnace is required for maintenance purposes.

While the embodiment of the present invention as herein disclosed, constitutes a preferred form, it is to be understood that other forms might be adopted, all coming within the scope of the claims which follow.

What is claimed is as follows:

1. Apparatus for heating longitudinally moving tubing comprising a bus bar connectible with a terminal of a current source, a rectangular carbon block fixed to the bar and in direct contact therewith and having a straight groove for receiving the leading portion of the tubing to be heated, said groove providing substantial area of contact with the tubing and remaining the same length as the tubing wears it deeper, means for urging the tubing against the block with constant unit pressure regardless of deepening of the groove in the block as the tubing wears it, a conductor spaced from the block rearwardly with respect to motion of the tubing for engaging a trailing portion of the tubing and means supporting the conductor and providing for electrical connection of the conductor with another terminal of the current source.

2. Apparatus according to claim 1 in which the tubing is urged against the carbon block by weighted blocks respectively resting upon portions of the tubing extending beyond the carbon block.

3. Apparatus according to claim 1 in which there is a heat insulated case which includes a metal bottom plate supported by and below the bus bar and electrically insulated therefrom, a heat insulating member secured upon the upper side of the bottom plate, an upwardly movable section having metallic top and side wall members, and heat insulating top and side members fixed to the inner surfaces of said metallic top and side wall members, the heat insulating side members being received upon the bottom heat insulating member when said section is in normal position, said section, when moved from normal position, exposing the groove in the block to facilitate threading the tubing.

4. Apparatus according to claim 1 having a base and means for supporting the bar above the base and including provisions for adjusting the bar relative to the base to obtain the required level of the groove in the carbon block as the groove deepens due to wear.

5. Apparatus according to claim 1 having a base, a horizontal shaft pivotally supported by the base and supporting the bus bar, a plate lo-

cated below and attached to the bus bar and electrically insulated therefrom and providing the bottom of the case, means in addition to the shaft for supporting the bus bar and including said plate and an adjustable strut connecting the plate with the base whereby the required level of the groove in the carbon block can be obtained as the groove deepens due to wear, the case having a movable section normally supported by the plate and enclosing the carbon block and means for pivotally connecting said case section with the shaft.

6. Apparatus according to claim 1 having a base, a horizontal shaft pivotally supported by the base and supporting the bus bar, a plate located below and attached to the bus bar and electrically insulated therefrom and providing the bottom of the case, means for adjusting the bar relative to the base to obtain the required level of the groove in the carbon block as the groove deepens due to wear, the case having a section normally supported by the plate and enclosing the carbon block, means for pivotally connecting said case section with the shaft, the means for urging the tubing against the carbon block comprising blocks extending through the top of the case section and guided thereby and engageable with portions of the tubing extending beyond the carbon block, rods each attached at one end to a second mentioned block, weights attached to the other ends of the rods, and a plate having holes receiving the rods and supported by the pivoted case section between the blocks and the weights.
